UNITED STATES PATENT OFFICE.

WILLIAM F. BUTLER, OF INDIANAPOLIS, INDIANA, ASSIGNOR TO SANITARY CAN COMPANY, OF NEW YORK, N. Y., A CORPORATION OF NEW YORK.

CAN-BODY-FLANGING MACHINE.

1,161,923.

Specification of Letters Patent. Patented Nov. 30, 1915.

Application filed October 30, 1909. Serial No. 525,432.

To all whom it may concern:

Be it known that I, WILLIAM F. BUTLER, a citizen of the United States, residing in Indianapolis, in the county of Marion and State of Indiana, have invented a new and useful Improvement in Can-Body-Flanging Machines, of which the following is a specification.

My invention relates to can body flanging machines.

The object of my invention is to provide a continuous rotary flanging machine of a simple, efficient and durable construction, by means of which can bodies may be rapidly and cheaply flanged, and the flanges formed with accuracy and uniformity, and without danger of cracking or injuring the sheet metal or rupturing the side seam of the can body.

My invention consists in a continuous rotary can body flanging machine comprising in coöperative combination a continuous rotary carrier for the can bodies and flanging tools or rollers, a plurality of flanging molds on the carrier, each having a hinged segment or jaw to open and close upon and clamp the can body, a stationary cam and connections for opening and closing the hinged segments or jaws of the molds as the carrier rotates, a curved shoe or guide for holding the hinged segments or jaws of the flanging molds securely and firmly but yieldingly closed during the flanging operation, side guides for centering the can bodies in the flanging molds before being clamped thereby, a feed chute for delivering the can bodies to the flanging molds, a plurality of rotatable and reciprocating flanging tool spindles axially in line with the flanging molds on the carrier, and each having a tool holder or arm carrying a flanging roller adapted to engage the projecting end of a can body in the flanging mold and coact with the mold to form a flange on the end of the can body, a central gear, preferably rotating in the opposite direction from the carrier and intermeshing with gears on the flanging tool spindles to rapidly rotate the same as they are conveyed around by the carrier, and stationary cams for reciprocating the flanging tool spindles as the carrier rotates. The fixed and

hinged half molds on the carrier are provided each with a can body ejector or arm which engages the can body when the hinged half mold opens and thus ejects the flanged can body from the mold and delivers it into the discharge chute as the carrier rotates. The side guides between which the flanging molds on the carrier pass are provided with converging and adjustable centering guides, preferably of a yielding character, or consisting of flat springs to accurately center the can bodies lengthwise in the flanging molds so that equal flanges will be turned or formed on each end of the can body by the flanging rollers which coact with the end faces of the molds.

Both ends of each can body are simultaneously flanged, the machine having two sets of axially rotating and reciprocating flanging tool spindles mounted on the carrier, one set at each end of the molds. The carrier is preferably composed of a number of separate heads secured together and rotating as a unit, and it is preferably supported and journaled on a central stationary or non-rotatable shaft fixed to the frame.

My invention also consists in the novel construction of parts and devices and in the novel combinations of parts and devices herein shown and described and more particularly specified in the claims.

One embodiment of my invention, and the preferred one, is illustrated in the accompanying drawing forming a part of this specification.

In said drawing, Figure 1 is a side elevation of a can body flanging machine embodying my invention. Fig. 2 is an end view. Fig. 3 is a detail, central, vertical section. Fig. 4 is a detail vertical section on line 4-4 of Fig. 3. Figs. 5, 6 and 7 are detail sections on lines 5-5, 6-6 and 7-7 of Fig. 4 respectively. Fig. 8 is a detail perspective view showing one of the flanging molds of the carrier. Fig. 9 is a detail section showing the side guides for centering the can bodies and the centering springs or devices with which the side guides are provided, and Fig. 10 is a detail section of one of the flanging molds and of the flanging rollers coacting therewith.

In the drawing, 11 represents the frame of

the machine, 12 a continuously rotating carrier, preferably supported and journaled upon a fixed or non rotating central shaft 13 supported in suitable brackets 14 on the frame of the machine. The carrier 12, for convenience of construction, is preferably composed of a number of separate pieces or heads 15, 16, 17 and 18. The continuously rotating carrier 12 is furnished with a plurality of flanging molds 19, preferably six in number each slightly less than the can body in length and conforming thereto in diameter, and each having a segment or jaw 20 adapted to open and close to receive and clamp the can body in the mold. The inner or fixed segment of the mold is preferably made integral with the heads 15 and 16 of the carrier. The hinged or opening and closing segment 20 of the mold is connected to the fixed segment by a hinge or pivot pin 21 and is opened and closed preferably by means of a stationary cam 22 secured to the fixed shaft 13 and fitting in a chamber 23 provided for it in the carrier heads 15, 16. Each of the hinged half molds or jaws 20 is furnished with an arm 24 connected by a link 25 having a roller 26 which travels in the stationary cam 22 as the carrier rotates. Each of the molds 19 has a registering shoulder or ledge 27 for the free edge 28 of the hinged jaw 20 to shut against. Each member of the flanging mold is also provided with an ejector or arm 29 fitting in the corresponding recess 30 of the other member of the mold when the hinged jaw of the mold is closed, and which engages the can body and operates to automatically eject the flanged can body from each member of the mold when the hinged member 20 opens, as will be readily understood from Fig. 8 of the drawing. The ejector arms or fingers 29 are preferably in separate pieces from the segments of the mold and secured thereto by screws. Two are preferably attached to the fixed member 19 of each mold and two to the hinged member 20 thereof. The can bodies 31 which are to be provided with flanges 32 at each end are automatically delivered one by one to the flanging molds by a delivery chute 33 to which the can bodies are fed by an elevator 34 having fingers 35. The feed chute 33 is preferably furnished with a curved spring holder 36 for retaining the last can body in the delivery end of the chute 33 until it is forced out of the chute into the open mold 19 on the carrier 12 by the fingers 35 acting upon adjacent can bodies in the chute 33.

After the hinged half molds or jaws 20 have been closed upon the can by operation of the stationary cam 22 and the connecting links 25, the jaws 20 are held firmly closed during the seaming operation by means of a curved guide or shoe 37 which is engaged by rollers 38 journaled on arms 39 of the jaws

20. The curved shoe or guide 37 is preferably yieldingly supported on the frame 11 of the machine by pins 40 fitting in slots or enlarged holes 41 in the shoe 37 and springs 42 mounted in brackets 43 and furnished with tension adjusting screws 44.

The flanging tool spindles 45, one for each flanging mold are mounted on the carrier 12 axially in line with the flanging molds and adapted to reciprocate, and each also to be rotated on its own axis. Each of these reciprocating and axially rotating flanging tool spindles 45 is furnished with a spur gear 46 which meshes with a central gear 47, the teeth of which are made wide enough to admit of the necessary longitudinal movement of the spindle 45 without disengaging its spur gear 46 from the central gear 47. The flanging tool spindles 45 are automatically reciprocated as required, preferably by means of stationary cams 48 on the frame of the machine, which are engaged by yoke levers 49 carrying rollers 50 for engagement with the cams and pivoted to lugs 51 on the head 18 of the carrier 12, and which yoke levers have pins engaging grooved collars 52 fixed to the spindles 45, a coiled spring 53 serving to retract the spindles 45.

Each of the flanging tool spindles 45 has secured thereto a tool holder or crank arm 54 furnished with a screw stud 55 upon which is journaled a flanging roller 56, the same being furnished with a curved face or shoulder 57 adapted to coöperate with the end face or shoulder 58 of the flanging mold 19, 20 to turn or form the flange 32 on the can body 31 as the flanging roller rotates on its own axis and is carried around the interior of the flanging mold by the axially rotating flanging tool spindle 45.

The central gear 47, instead of being stationary or fixed to the central shaft 13 is rotated in the opposite direction from the carrier 12 and is furnished with a sleeve 59 surrounding the central shaft 13 carrying a gear 60 which meshes with a gear 61 on the countershaft 62 which meshes with a gear 63 on the shaft 64. The carrier 12 is furnished with a spur gear 65 preferably in a separate piece from the head 18 and bolted thereto, and which meshes with a gear 66 on the shaft 64. The shaft 64 and the gears 60, 61, 63, 65 and 66 and countershaft 62 are duplicated at each end of the machine and one of the shafts 64 is furnished with a driving pulley 67.

After the can bodies are flanged they are discharged from the flanging molds into a discharge chute 68 which delivers them to the elevator or conveyer 69 for the flanged can bodies.

In order to accurately center the can bodies in the flanging molds so that the flanges will be formed equal and uniform at each

end of the can body, I provide the side guides 70 on the frame of the machine and between which the flanging molds pass as the carrier rotates with slightly converging and adjustable centering guides 71, the same fitting in slots 72 in the side guides 70 and secured thereto at one end by screws 73 and fitting at their free ends against adjusting screws 74. The centering guides 71 are preferably of a yielding character or composed of flat springs so that the outer ends of the springs may yield and permit an abnormally long can body to pass without binding or sticking. The side guides 70 are cut away, as will be readily understood from Fig. 3, to admit the flanging rollers into the ends of the can bodies.

I claim:—

1. In a can body flanging machine, the combination with a continuously rotating carrier, of a plurality of flanging molds on the carrier each having a hinged jaw, and a plurality of reciprocating and axially rotating flanging tool spindles mounted on said carrier axially in line with said flanging molds and having crank arms carrying axially rotatable flanging rollers turning about axes extending lengthwise of said spindles, and a curved shoe for holding the hinged jaws of the flanging molds closed during the flanging operation, substantially as specified.

2. In a can body flanging machine, the combination with a continuously rotating carrier, of a plurality of flanging molds on the carrier each having a hinged jaw, and a plurality of reciprocating and axially rotating flanging tool spindles mounted on said carrier axially in line with said flanging molds and having crank arms carrying axially rotatable flanging rollers turning about axes extending lengthwise of said spindles, a curved shoe for holding the hinged jaws of the flanging molds closed during the flanging operation, a stationary cam and connections for opening and closing the hinged jaws of said molds, and stationary cams for reciprocating said flanging tool spindles as the carrier rotates, substantially as specified.

3. In a can body flanging machine, the combination with a continuously rotating carrier, of a plurality of flanging molds on the carrier each having a hinged jaw, and a plurality of reciprocating and axially rotating flanging tool spindles mounted on said carrier axially in line with said flanging molds and having crank arms carrying axially rotatable flanging rollers turning about axes extending lengthwise of said spindles, a curved shoe for holding the hinged jaws of the flanging molds closed during the flanging operation, a stationary cam and connections for opening and closing the hinged jaws of said molds, stationary cams

for reciprocating said flanging tool spindles as the carrier rotates, a central gear, and gears on said spindles meshing with said central gear for rotating said spindles, substantially as specified.

70

4. In a can body flanging machine, the combination with a continuously rotating carrier, of a plurality of flanging molds on the carrier each having a hinged jaw, and a plurality of reciprocating and axially rotating flanging tool spindles mounted on said carrier axially in line with said flanging molds and having crank arms carrying axially rotatable flanging rollers, and side guides between which said molds pass as the carrier rotates, substantially as specified.

75

5. In a can body flanging machine, the combination with a continuously rotating carrier, of a plurality of flanging molds on the carrier each having a hinged jaw, and a plurality of reciprocating and axially rotating flanging tool spindles mounted on said carrier axially in line with said flanging molds, and having crank arms carrying axially rotatable flanging rollers, side 90 guides between which said molds pass as the carrier rotates, and converging centering guides for centering the can bodies in the flanging molds, substantially as specified.

95

6. In a can body flanging machine, the combination with a continuously rotating carrier, of a plurality of flanging molds on the carrier each having a hinged jaw, and a plurality of reciprocating and axially rotating flanging tool spindles mounted on said carrier axially in line with said flanging molds and having crank arms carrying axially rotatable flanging rollers turning about axes extending lengthwise of said spindles, said carrier having a plurality of 100 separate piece heads furnished with a central chamber, and a stationary cam in said chamber for opening and closing the hinged jaws of the molds as the carrier rotates, substantially as specified.

110

7. In a can body flanging machine, the combination with a continuously rotating carrier, of a plurality of flanging molds on the carrier each having a hinged jaw, and a plurality of reciprocating and axially rotating flanging tool spindles mounted on said carrier axially in line with said flanging molds and having crank arms carrying axially rotatable flanging rollers turning about axes extending lengthwise of said 120 spindles, and a central gear rotating in the opposite direction from the carrier and gears on said spindles meshing with said central gear, substantially as specified.

115

8. The combination with a carrier, of a plurality of half molds thereon each having an ejector, and a plurality of hinged half molds each having a can body ejector, substantially as specified.

125

9. The combination with a can body flang-

130

ing half mold having an ejector arm fixed thereto, of a hinged half mold having an ejector arm fixed thereto, substantially as specified.

5 10. The combination with a can body flanging half mold having an ejector arm fixed thereto, of a hinged half mold having an ejector arm fixed thereto, each of said half molds having a recess to receive the 10 ejector on the other when the hinged mold is closed, substantially as specified.

11. In a can body flanging machine, the combination with a continuously rotating carrier, of a plurality of flanging molds on 15 the carrier each having a hinged jaw, said hinged jaws swinging about an axis parallel to the axis of rotation of the carrier, and a plurality of reciprocating and axially rotat- 20 ing flanging tool spindles mounted on said carrier axially in line with said flanging molds and having crank arms carrying ax- 25 ially rotatable flanging rollers, and a spring pressed curved shoe for holding said hinged jaws closed during the flanging operation, substantially as specified.

12. In a can body flanging machine, the combination with a continuously rotating carrier, of a plurality of flanging molds on the carrier each having a hinged jaw said 30 hinged jaws swinging about an axis parallel to the axis of rotation of the carrier, and a plurality of reciprocating and axially rotat- 35 ing flanging tool spindles mounted on said carrier axially in line with said flanging molds and having crank arms carrying ax- 40 ially rotatable flanging rollers, and a spring pressed curved shoe for holding said hinged jaws closed during the flanging operation, said hinged jaws carrying rollers engaging said shoe, substantially as specified.

13. In a can body flanging machine, the combination with a continuously rotating carrier, of a plurality of flanging molds on the carrier each having a hinged jaw, and a 45 plurality of reciprocating and axially rotat- 50 ing flanging tool spindles mounted on said carrier axially in line with said flanging molds and having crank arms carrying axially rotatable flanging rollers turning 55 about axes extending lengthwise of said spindles, a stationary cam and connections for opening and closing said hinged jaws as the carrier rotates, substantially as specified.

14. In a can body flanging machine, the 55 combination with a continuously rotating carrier, of a plurality of molds thereon each having a hinged jaw, a plurality of recip- 60 roating and axially rotating flanging tool spindles on said carrier at the opposite ends of said molds and axially in line therewith, each having a crank arm provided with a flanging roller, substantially as specified.

15. In a can body flanging machine, the combination with a continuously rotating

carrier, of a plurality of molds thereon each 65 having a hinged jaw, a plurality of reciprocating and axially rotating flanging tool spindles on said carrier at the opposite ends of said molds and axially in line therewith, each having a crank arm provided with a 70 flanging roller, and stationary cams for reciprocating said spindles, substantially as specified.

16. In a can body flanging machine, the combination with a continuously rotating 75 carrier, of a plurality of molds thereon each having a hinged jaw, a plurality of reciprocating and axially rotating flanging tool spindles on said carrier at the opposite ends of said molds and axially in line therewith, 80 each having a crank arm provided with a flanging roller, stationary cams for reciprocating said spindles, and springs for returning said spindles to position, substantially as specified.

17. In a can body flanging machine, the combination with a continuously rotating carrier, of a plurality of molds thereon each having a hinged jaw, a plurality of reciprocating and axially rotating flanging tool 90 spindles on said carrier at the opposite ends of said molds and axially in line therewith, each having a crank arm provided with a flanging roller, stationary cams for reciprocating said spindles, springs for returning 95 said spindles to position, a pair of central gears, and gears on said spindles meshing with said central gears, substantially as specified.

18. In a can body flanging machine, the 100 combination with a continuously rotating carrier, of a plurality of molds thereon each having a hinged jaw, a plurality of recip- 105 roating and axially rotating flanging tool spindles on said carrier at the opposite ends of said molds and axially in line therewith, each having a crank arm provided with a flanging roller, stationary cams for reciprocating said spindles, springs for returning 110 said spindles to position, a pair of central gears, gears on said spindles meshing with said central gears, a stationary cam and connections for opening and closing said hinged jaws, substantially as specified.

19. In a can body flanging machine, the 115 combination with a continuously rotating carrier, of a plurality of molds thereon each having a hinged jaw, a plurality of recip- 120 roating and axially rotating flanging tool spindles on said carrier at the opposite ends of said molds and axially in line therewith, each having a crank arm provided with a flanging roller, stationary cams for reciprocating said spindles, springs for returning 125 said spindles to position, a pair of central gears, gears on said spindles meshing with said central gears, a stationary cam and connections for opening and closing said

hinged jaws, and a curved shoe for holding the hinged jaws closed during the flanging operation, substantially as specified.

20. In a can body flanging machine, the combination with a continuously rotating carrier, of a plurality of molds thereon each having a hinged jaw, a plurality of reciprocating and axially rotating flanging tool spindles on said carrier at the opposite ends 10 of said molds and axially in line therewith, each having a crank arm provided with a flanging roller, stationary cams for reciprocating said spindles, springs for returning said spindles to position, a pair of central 15 gears, gears on said spindles meshing with said central gears, stationary cams and connections for opening and closing said hinged jaws, a curved shoe for holding the hinged jaws closed during the flanging operation, 20 and side guides furnished with centering devices, substantially as specified.

21. In a can body flanging machine, the combination with a rotating carrier, of a plurality of flanging molds on the carrier 25 each having a movable jaw, and a plurality of reciprocating and axially rotating flanging tool spindles mounted upon said carrier axially in line with said flanging molds and flanging tools carried by said spindles and 30 rotating about axes parallel to said spindles, and a shoe for holding the movable jaws of said molds closed, substantially as specified.

22. In a can body flanging machine, the combination with a rotating carrier, of a plurality of flanging molds on the carrier 35 each having a movable jaw, and a plurality of reciprocating and axially rotating flanging tool spindles mounted upon said carrier axially in line with said flanging molds and flanging tools carried by said spindles and 40 rotating about axes parallel to said spindles, a shoe for holding the movable jaws of said molds closed, and a spring bearing against said shoe, substantially as specified.

45. 23. In a can body flanging machine, the combination with a rotating carrier, of a plurality of flanging molds on the carrier each having a movable jaw, and a plurality of reciprocating and axially rotating flanging 50 tool spindles mounted upon said carrier axially in line with said flanging molds and flanging tools carried by said spindles, side guides between which the molds on said carrier pass, and converging guides, substantially as specified.

24. In a can body flanging machine, the combination with a rotating carrier, of a plurality of flanging molds on the carrier, each having a movable jaw, a plurality of 60 reciprocating and axially rotating flanging tool spindles mounted upon said carrier axially in line with said flanging tools, flanging tools carried by said spindles and rotating about axes parallel to said spindles,

a central gear, gears on said spindles meshing with said central gear for rotating said spindles as the carrier revolves, and means for rotating said central gear in the opposite direction from the carrier, substantially as specified.

25. In a can body flanging machine, the combination with a rotating carrier having a plurality of molds thereon each of which is adapted to receive a can therein, of a plurality of rotating flanging tool spindles 70 mounted on said carrier and rotatable therewith, the flanging tool spindles being arranged in pairs one at each end of each mold and alined therewith, each of said spindles having a flanging roller thereon the axes of which is eccentric to and revoluble around the axis of the spindle, substantially as specified.

26. In a can body flanging machine, the combination with a rotating carrier having 85 a plurality of flanging molds thereon each of which is adapted to receive a can body therewithin, of a plurality of reciprocating and axially rotating flanging tool spindles mounted on said carrier and bodily movable therewith, the spindles being arranged at opposite ends of said molds to thereby flange the cans at both ends simultaneously, each of said spindles being provided with a flanging roller the axis of which is eccentric 90 to and revoluble around the axis of the spindle, the rollers being coöperable with the molds, substantially as specified.

27. In a can body flanging machine, the combination with a carrier rotatable about 100 a horizontal axis, said carrier having a plurality of flanging molds thereon in which are adapted to be received the can bodies, of a plurality of reciprocating and axially rotating flanging tool spindles mounted on 105 said carrier axially in line with said flanging molds, each of said spindles having a crank arm having a flanging roller mounted thereon, the flanging rollers coöperating with said molds to thereby flange the ends 110 of the can bodies, substantially as specified.

28. In a can body flanging machine, the combination with a carrier continuously rotatable about a horizontal axis, said carrier having a plurality of flanging molds thereon, each mold including a hinged jaw, of a plurality of flanging tool spindles mounted on and carried by said carrier, said spindles being axially rotatably mounted and in alinement with the flanging molds, each 120 of said spindles being provided with a flanging roller at its inner end, and means for reciprocating said spindles toward and from the molds as the carrier rotates, substantially as specified.

29. In a can body flanging machine, the combination with a carrier continuously rotatable about a horizontal axis, said carrier

having a plurality of flanging molds thereon, each mold including a hinged jaw, of a plurality of flanging tool spindles mounted on and carried by said carrier, said spindles being axially rotatably mounted and in alinement with the flanging molds, each of said spindles being provided with a flanging roller at its inner end, means for reciprocating said spindles toward and from

the molds as the carrier rotates, and automatically operable means for opening and closing said hinged jaws as the carrier rotates, substantially as specified.
